EMERY H. FAHRNEY, OF CHICAGO, ILLINOIS

MEANS FOR PROTECTING THE PROPELLER AND RUDDER OF BOATS

Application filed December 22, 1928. Serial No. 327,781.

Heretofore with boats in which the propeller or the rudder, or both, project below the bottom of the boat, they are frequently damaged by contacting with a projecting 5 submerged rock or other object or by reason of contact with the bottom in shallow water.

It is one of the objects of the present invention to improve the means for mounting and securing or holding the propeller, or the 10 rudder, or both, in an operative position so that they will project below the boat bottom during normal conditions but will yield when struck by a submerged object which would otherwise damage the same, or when 15 running aground or into shallow water.

To the attainment of these ends and the accomplishment of other new and useful objects as will appear, the invention consists in the features of novelty in substantially 20 the construction, combination and arrangement of the several parts hereinafter more fully described and claimed and shown in the accompanying drawings illustrating this invention and in which

25 Figure 1 is a view partly in vertical section and partly in elevation of the rear portion of a boat having an attachment constructed in accordance with the principles of this invention applied thereto.

30 Figure 2 is a view similar to Figure 1, with parts omitted and showing the position the attachment will take when released by contact with a projecting object.

Figure 3 is a detail sectional view taken on 35 line 3—3, Figure 2.

Figure 4 is a horizontal sectional view taken on line 4—4, Figure 1.

Referring more particularly to the drawings the numeral 10 designates a boat having arranged therein the usual engine or motor 11. Connected to the engine shaft is a coupling member 12, and which coupling member is located in alignment with and preferably adjacent an opening 13 in the 45 back 14 of the boat.

Encompassing the opening 13 and secured to the outer face of the back 14 is a member 15 having an opening 16 therein registering with the opening 13 and encompassing the 50 opening 16 is a packing gland 17.

The member 15 is preferably provided with spaced projecting ears 18, preferably arranged adjacent the top thereof and similarly projecting ears 19 arranged adjacent the bottom thereof, the member 15 being secured to the boat back in any desired or suitable manner, such as by means of fastening devices 20.

A supporting member or frame designated generally by the reference numeral 21 is provided with bearings 22—23 in which a vertical shaft 24 is journaled, the shaft being arranged within a chamber 25 and extending through a tubular extension 26 and has an operative connection with a propeller 27.

Loosely mounted upon the shaft 24 for rotation therewith are gear wheels 28—29 preferably of the beveled type, which mesh with a beveled gear 30, the latter being secured to a shaft 31 for rotation therewith and connected with the shaft 31 is a coupling member 32 which projects for some distance beyond the casing 25. Keyed to the shaft 24 is a clutch member 33 which is

adapted to be moved longitudinally of the shaft by means of an operating lever 34 arranged in a convenient position for the operator. Clutch faces 35—36 are provided on the clutch member 33 and these clutch faces respectively cooperate with clutch faces

37—38 respectively secured to the gears 28—29 so that when the clutch member 33 is shifted, one or the other of the gears 28—29 may be connected with the shaft 24 for rotation therewith, the direction of rotation of the shaft being controlled by the respective gears 28—29.

The supporting structure 21 is provided with spaced ears 39 which are adapted to be connected with the ears 18 on the member 15 by means of a suitable fastening pin or shaft 40 so that the entire structure or frame 21 with the propeller shaft and propeller together with the gears 28, 29 and 30 and the actuating lever 34 may be swung about the pivot formed by the shaft 40. When the supporting structure 21 is in the position shown in Figure 1 the coupling member 12 will pass through the openings 16 and 13 respectively in the members 15 and the wall

14 of the boat to engage and cooperate with the coupling member 12 on the shaft of the engine or motor 11, thereby connecting the shaft 31 with the motor.

5 In order to hold the parts in this position the supporting structure 21 is preferably provided with additional ears 41 which are adapted to be positioned adjacent the ears 19 on the member 15 and a fastening member 42 in the form of a pin or bolt is passed through the cooperating ears for holding the supporting structure 21 in the position shown in Figure 1.

10 This fastening pin or bolt 42 is constructed of some frangible material or material adapted to be sheared or cut when undue strain is placed thereupon, so that when the parts are in the position shown in Figure 1 and when the boat is advancing, should the depending portion of the supporting structure 21 strike a projecting submerged object or the bottom when in shallow water, the fastening device or pin 42 will be sheared, cut or broken so as to allow the supporting structure 21 to swing to the position shown in Figure 2 about the pivot 40, or to a sufficient extent to allow the depending portion of the supporting structure 21 to pass over the projecting object or drag along the bottom in shallow water, thereby preventing the propeller and operating mechanism therefor from being injured. When the supporting structure swings to the position shown in Figure 2, the coupling members 32-12 will readily separate to permit of such movement.

15 If desired, the supporting structure 21 may be provided with suitable bearings 43 for the rudder shaft 44 to which the rudder 45 is connected and the rudder is adapted to be actuated by means of the usual tiller arm or lever 46.

20 It has been found that the pin or bolt 42 is not always necessary. That is to say, if the pin or bolt is omitted the propeller and the supporting frame therefor will be held in the position shown in Figure 1, by the action of the propeller upon the water, when the boat is advancing, as the propeller exerts a pressure upon the water in a direction to force the supporting frame or structure 21 against the end of the boat. However, when the boat is being propelled backwardly, the pin 42 will be necessary.

25 With this improved construction it will manifest that the device may be readily applied to a boat and when in use will be protected against injury.

30 While the preferred form of the invention has been herein shown and described, it is to be understood that various changes may be made in the details of construction and in the combination and arrangement of the several parts, within the scope of the claims,

without departing from the spirit of this invention.

What is claimed as new is:—

1. In combination, a boat, a motor therein fixed against bodily movement, a propeller, a support for the propeller, a propeller shaft, means connecting the propeller support to the boat, for swinging movement with respect to the motor, means yieldingly holding the propeller in a position to project below the boat bottom, the last recited means embodying an element destructible under abnormal stress, and a separable connection between the propeller shaft and the motor. 70

2. In combination, a boat, a motor therein fixed against bodily movement, a propeller, a support for the propeller, a propeller shaft, means connecting the support to the boat for pivotal movement on an axis transverse to the longitudinal axis of the boat, means yieldingly holding the said support in a position that the propeller will be disposed below the boat, the last recited means embodying an element destructible under abnormal pressure, and a separable connection between the propeller shaft and the motor. 80

3. In combination, a boat, a motor therein fixed against bodily movement, a propeller, a support for the propeller, a propeller shaft, means connecting the support to the boat for pivotal movement on an axis transverse to the longitudinal axis of the boat, a fastening element for maintaining said support from swinging movement about its pivot, said fastening means being destructible under abnormal strain and a separable connection between the propeller shaft and the motor. 95

4. In combination, a boat, a driving shaft therein, a support, means mounting the support for swinging movement with respect to the boat, a propeller carried by the support, means for maintaining the support against swinging movement under normal conditions, the last said means being yieldable under abnormal conditions, and means whereby the swinging movement of the said support will connect and disconnect the propeller respectively with and from the said driving shaft, the second recited means embodying an element destructible under abnormal stress thereupon. 105

5. In combination a craft, propelling mechanism therefor, said propelling mechanism projecting from the craft and into the water, a motor in the craft fixed against bodily movement, means for maintaining the propelling mechanism against bodily movement with respect to the shaft, the said means being adapted to automatically yield under abnormal conditions whereby the said propelling means will bodily shift with respect to the craft, the said means also embodying an element destructible under an abnormal stress and a separable connection between the propeller shaft and the motor. 110

6. In combination, a craft, steering mechanism therefor, said steering mechanism projecting from the craft and into the water, a motor for the craft fixed against bodily movement, means for maintaining the steering mechanism against bodily movement with respect to the craft, the said means being adapted to automatically yield under abnormal conditions whereby the said steering mechanism will bodily shift with respect to the craft, the said means also embodying an element destructible under an abnormal stress, and a separable connection between the propeller mechanism and the motor.

15 In testimony whereof, I have signed my name to this specification on this 18th day of December, 1928.

EMERY H. FAHRNEY.
